UNITED STATES PATENT OFFICE.

CHARLES E. COOKE, OF ATLANTIC CITY, NEW JERSEY.

HAT-FASTENER.

1,168,167.

Specification of Letters Patent.

Patented Jan. 11, 1916.

Application filed August 8, 1914. Serial No. 255,776.

To all whom it may concern:

Be it known that I, CHARLES E. COOKE, a subject of the King of Great Britain, residing at Atlantic City, in the county of Atlantic and State of New Jersey, have invented new and useful Improvements in Hat-Fasteners, of which the following is a specification.

An object of the invention is to provide 10 a simple and effective device for readily securing a hat upon the head of the wearer, and which will take the place of the usual hat pin and, furthermore, will obviate the necessity of punching holes or perforations 15 in the hat and thus mutilating the same, as is the case when the ordinary hat pins are used.

The invention comprehends, among other features, the provision of a simple and effective device which can be readily applied 20 to any form or shape of hat and which is preferably made of gold, silver or some other neat appearing metal, the device being so arranged and constructed whereby the 25 user, after placing the hat upon the head, can readily secure the hat against accidental removal by having certain pins forming a part of the device arranged to engage the hair and thus secure the hat.

30 In the further disclosure of the invention reference is to be had to the accompanying drawings, constituting a part of this specification, in which similar characters of reference denote corresponding parts in all the 35 views, and in which:

Figure 1 is a perspective view of the device; Fig. 2 is a fragmentary vertical sectional view of a hat showing the device applied thereto; and Fig. 3 is a horizontal sectional view taken through the plate and showing the means for securing the same within the crown of the hat.

Referring more particularly to the views, 45 I disclose a hat 10 having the usual crown 11 and lining 12, with the usual brim 13 attached to or formed with the crown 11. A plate 14, is provided with a series of apertures 15 and an edge 16 of the plate is 50 formed to provide a longitudinal groove 17 defining the rib 17' as shown, and upon which are arranged to slide clamp members 18 of U-shaped formation, each consisting 55 of a head 19 and a pin 20 projecting from the head and extending longitudinally to the plate, said pins 20 of the said securing

members being arranged to extend in opposite directions and projecting into the lining 12 of the hat, thus hingedly supporting the plate 14 within the crown, it being understood that one of the plates is provided on 60 each side of the hat. One of the limbs of each clamp 18 has a portion positioned in the groove 17 and its other limb engaging the rib 17' thereby holding said clamps upon the plate 14. 65

A bar 21 has a series of perpendicularly extending pins 22 secured thereto, with the outer ends of the pins terminating in knobs 23 and which are preferably made larger than the apertures 15 and the pins 22 slide 70 through the apertures 15, as shown.

In the application of the device described to a hat and in the use thereof, the hat is first placed upon the head of the wearer, with the knobs closest to the plate 14, the 75 said bar 21 constituting a handle. The wearer now grasps the bars on each side and, pushing upwardly and inwardly thereon, causes the pins 22 and the knobs 23 thereof to pass through the hair and secure 80 the hat against accidental removal from the head, it being thus seen that when the hat is secured as mentioned the bars of the device will lie adjacent to the plates 14 thereof and the pins, passing into the hair, together 85 with the knobs 23 of the pins, will tend to hold the hat in position and against displacement.

It will be understood that the plate 14 and bar 21 can be removed from as readily as 90 they can be applied to a hat.

It will be furthermore noted that with a device of the character described the perforating of the crown of the hat is obviated and the device, particularly when made up 95 in gold or silver and appropriately ornamented with jewels or the like, will present a neat and effective appearance.

Having thus described my invention, I 100 claim:

1. A hat fastener comprising an elongated plate having a longitudinally disposed groove adjacent one edge thereof, a U-shaped clamp embracing said edge and having a portion disposed within the groove for retaining the same thereon for sliding movement, a fastening element carried by said clamp for securing the plate upon the hat, and hair engaging means carried by said plate. 105 110

2. A hat fastener comprising an elongated plate having a longitudinally disposed groove on one face thereof and defining a bead on the opposite face thereof, a U-shaped clamp slidably mounted on said edge and having one of its limbs positioned within the groove, and its opposite limb engaging said bead, a fastening element carried by the clamp for securing the plate

upon the hat, and hair engaging means carried by said plate.

In testimony whereof I affix my signature in presence of two witnesses.

CHARLES E. COOKE.

Witnesses:

H. F. LETHERMAN,
FRED R. NEAL.
